UNITED STATES PATENT OFFICE.

JOSEPH A. GROEBLI, OF NEW YORK, N. Y., ASSIGNOR TO THE KURSHEEDT MANUFACTURING COMPANY, A CORPORATION OF NEW YORK.

COUPLING MECHANISM FOR EMBROIDERING-MACHINES.

No. 902,816.

Specification of Letters Patent.

Patented Nov. 3, 1908.

Application filed January 19, 1907. Serial No. 353,034.

To all whom it may concern:

Be it known that I, JOSEPH A. GROEBLI, a citizen of the United States, and a resident of the city, county, and State of New York, have invented certain new and useful Improvements in Coupling Mechanism for Embroidering-Machines, of which the following is a specification.

My invention relates to coupling mechanism for coupling the fabric frames of embroidery machines to their moving mechanism, but I have herein used such designating title only by reason of the fact that the present embodiment of my invention is shown embodied in an embroidery organism consisting of the fabric frame of an embroidery mechanism *per se* and a jacquard connection coupled together.

In the accompanying drawings in which I have shown one embodiment of my invention, Figure 1 is a side view partly broken away showing one form of mechanism in which my invention is embodied, Fig. 2 is a section on the line 2—2 of Fig. 1 looking in the direction of the arrow, Fig. 3 is a side elevation of the compound actuating block with one of its half shells cut away for illustrative purposes; Fig. 4 is a section on the line 4—4 of Fig. 3 with both half shells in place on the curved middle portion or pin, Fig. 5 is a view similar to Fig. 3 showing the middle of the pin rectangular and on opposite sides of said middle portion two sets of wings or shells, Fig. 6 is a section on the line 6—6 of Fig. 5, Figs. 7 and 8 are views similar to Figs. 3 and 4 showing another form of block in which the pin is entirely surrounded by a sleeve with plain facets.

In U. S. Letters Patent No. 528632, dated Nov. 6, 1894, I have shown, (see particularly Figs. 4, 15, 16, 17 and 18 and lines 119 page 2 to line 11 page 3 of said patent) a jacquard mechanism and an embroidery mechanism coupled by a pin and roller (bowl) device *b*. I have found however, that this arrangement is not the most ideal device for the purpose by reason of wear and other causes. It also occurs that, the fabric frame being of considerable length (thirty feet) the tension of the fabric stretched on the frame or other stress or condition will cause the frame to warp slightly and thus warp the plane of the fabric frame and cause the coupling between the guides B and C and the jacquard to bear against the ways or slots in the guides caus-

ing the coupling to bind unless it be made flexible in the direction of the strain.

My present invention is designed primarily to obviate this and other difficulties should they occur.

It will be observed that some of the parts in the drawings of the patent referred to are lettered similarly to the corresponding parts in this application.

In the drawing of the patent and in the drawings of this application A indicates the fabric frame of an embroidery mechanism having in the present instance a depending arm *a* provided with a pin *c*, which enters and is fastened in guide or actuating blocks placed at opposite ends of the pin *c*, one of which works in a slot in the guide B and the other of which blocks works in a slot in the guide C.

In the drawings of this application the guides B, C, cross each other, the guide B being connected to the rack *d*, and the guide C connected to the rack *e*, see Fig. 2. The rack *d*, meshes with the pinion *f*, on the rotatable shaft D, forming part of the jacquard and the rack *e*, which is shown broken away meshes with a similar pinion carried on a similar shaft of the jacquard. (See pinion *g*, on shaft D² Fig. 7, Sheet 7 of the drawing and lines 5 to 10, page 3, of Patent 528632, herein referred to). The block G, may take many forms, three of which I have illustrated in the drawing. In the forms shown herein the idea is embodied of using a pin or stud having curved sides (not necessarily circular) surrounded or partly so by a set of saddles, wings or shells or surrounded by a sleeve or set of sleeves. In each case the outer facets or faces of the saddles or sleeves are shown as conforming to the shape of the grooves in the cross guides B and C. The pin *c*, enters a hole in the body of the block G and is held firmly therein. For the purpose of this specification and that alone, I have shown the block as squared in each case.

Referring for the present to Figs. 3 and 4 it will be seen that the block G consists of a body portion *g*, apertured at *g'* for the passage of the pin *c*, on the arm *a*, of the fabric frame A. This body portion has curved sides *g²* and end flanges or retainers *g⁴* of washer like appearance. Riding upon the curved sides *g²* between the flanges *g⁴* are freely sliding pieces *g⁵* hereinbefore and hereinafter termed saddles although this is merely

for convenience of nomenclature as they might just as readily be termed shells or wings or any other appropriate designation. It will be observed that the space between 5 the opposite edges of the two saddles g^6 constituting the set will allow the body g of the block to swing in the saddles on its axis.

In Figs. 5 and 6 I have shown a similar block G^1 . This block G^1 is shown as having 10 at the middle portion of its body g^{10} a squared portion g^{11} through which the aperture for the pin c passes. Flanking the middle portion g^{11} on either side thereof are rounded or cylindrical portions g^{12} terminating in collars, flanges or washers g^{13} g^{14} . Seated on these portions g^{12} are saddles g^{15} 15 g^{16} in which these curved portions g^{12} are adapted to swing. In this construction as in the construction just described, the faces 20 of the saddles where they contact with the sides of the ways in the guides B and C extend beyond the end flanges g^{13} g^{14} so that these end flanges do not contact with the guides.

25 In Figs. 7 and 8 I have shown a block G^2 with the curved or cylindrical body portion g^{20} having a flange g^{21} at one end and capped at the other end by a washer g^{22} held in place by a screw g^{23} passing through the washer 30 and tapped into the block g^{20} . Intervening between the flange and washer is a sleeve g^{24} herein shown as rectangular on the outside and as conforming to the shaft of the body g^{20} of the block G^2 . The body g^{20} of the 35 block G^2 is apertured at g^{25} for the reception of the pin c and the sleeve g^{24} is apertured at g^{26} for the passage of the pin c , the aperture g^{26} in the particular construction shown being larger than the aperture g^{25} to allow for the 40 swing of the pin c .

It is thought that the operation of all the devices shown and described will be obvious from the description and illustration.

While I have herein specifically shown 45 described and to some extent specifically claimed certain constructions, I would have it understood that I do not limit myself to the devices described and shown, as the devices may be greatly varied without departing 50 from the spirit of my invention.

Having described my invention, what I claim is:—

1. In a mechanism of the class described, a fabric frame and means for moving the same, 55 comprising a guide and moving means for the guide and a coupling for coupling the fabric frame and guide, including a coupling block having a body portion adapted to swing on an axis substantially parallel to the 60 plane of the guide and a filling member engaging the guide and in which the body of the block is adapted to swing.

2. In a mechanism of the class described, a fabric frame and a guide adapted to move 65 the same, means for moving the guide, and a

coupling for coupling the fabric frame and guide, including a coupling block having a body portion adapted to swing on an axis substantially parallel to the plane of the guide and a filling member engaging with 70 and conforming to the part of the guide with which it engages.

3. In a mechanism of the class described the combination of an embroidering frame, means for moving the same and means for 75 coupling the frame and moving means, comprising a body portion and a filling piece engaging with the moving means and in which the body portion may swing.

4. In a mechanism of the class described, 80 the combination of an embroidering frame, means for moving the same comprising a guide and means for moving the guide, and means for coupling the said frame and guide, including a body portion having circular 85 faces and filling pieces conforming to said guide and in which the circular faces of said body are adapted to move.

5. In a mechanism of the class described, 90 the combination of an embroidering frame, a guide for moving the same, means for moving the guide and a coupling for the frame and guide including a body portion, filling means engaging with said guide and in which said body portion moves and means on 95 said body portion to prevent longitudinal displacement of said filling means from said body.

6. In a mechanism of the class described, 100 the combination of an embroidering frame, a guide for moving the same, means for moving the guide and a coupling for the frame and guide including a body portion, filling means engaging with said guide and in which said body portion moves and flanges on said 105 body portion, within the lateral limits of the filling means, adapted to prevent the displacement of the filling means.

7. In a mechanism of the class described, the combination of a fabric frame, a plurality 110 of substantially parallel guiding members adapted to move said frame, and provided with guiding grooves on their opposing faces and means for coupling said frame between said guiding members including a plurality 115 of frame members adapted to be moved by said guides and a plurality of filling pieces conforming to the grooves in the guiding members and in which the said frame members are adapted to swing, the said filling 120 pieces being adapted to travel with the frame members.

Signed at New York, in the county of New York, and State of New York, this 18th day of January 1907

JOSEPH A. GROEBLI.
